(57) **CLAIM**

The ornamental design for a foot massager, as shown and described.

DESCRIPTION

FIG. 1 is a front, left and bottom perspective view of a foot massager, showing our new design;

FIG. 2 is a rear, right and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion of FIG. 1 thereof; and,

FIG. 10 is an enlarged view of portion of FIG. 1 thereof.

The dash-dot broken lines shown in FIGS. 1, 9 and 10 are for the purpose of showing enlarged areas and form no part of the claimed design.

The broken lines shown in the drawings illustrate portions of the foot massager that form no part of the claimed design.

1 Claim, 10 Drawing Sheets
